INVENTOR

By his Atty David True,
Henry Williams

UNITED STATES PATENT OFFICE.

DAVID TRUE, OF AMESBURY, MASSACHUSETTS.

NOZZLE FOR OIL-CANS.

SPECIFICATION forming part of Letters Patent No. 576,702, dated February 9, 1897.

Application filed January 2, 1896. Serial No. 574,079. (No model.)

To all whom it may concern:

Be it known that I, DAVID TRUE, a citizen of the United States, residing in Amesbury, in the county of Essex and State of Massachusetts, have invented new and useful Improvements in Nozzles for Oil-Cans, of which the following is a specification.

This is an improved nozzle adapted to be applied to oil-cans of any description, preferably, but not necessarily exclusively, to oil-cans for use in connection with machinery and which are adapted to apply oil to bearings which are at some little distance from the hand or in obscure locations or at points not easily seen or accessible.

The invention consists in the construction hereinafter described, whereby a yielding quality is applied to the nozzle, so that while it is normally straight it is sufficiently pliable to yield and bend rather than become broken by the exercise of a force which would bend or break an ordinary nozzle, and whereby said yielding nozzle is applied to the oil-reservoir.

The nature of the invention in detail is fully described below, and illustrated in the accompanying drawings, in which—

Figure 1 is an elevation of my improved nozzle applied to an oil-can. Fig. 2 is an enlarged vertical section of a sufficient portion 30 of the nozzle to illustrate the invention. Fig. 3 is a horizontal section on line *x*, Fig. 2. Fig. 4 is a horizontal section on line *y*, Fig. 2.

Similar letters of reference indicate corresponding parts.

A represents the body or reservoir of an ordinary oil-can. B is the tip of the nozzle. This tip is rigid with the tube C, and an annular shoulder B' is formed at the point where the upper end of the tube C joins the lower 40 end of the tip B. Within the tube C is rigidly placed a plug or core D of even length therewith whose periphery is corrugated or provided with longitudinal grooves D'. Driven into the lower end of the central passage D' in the plug D is the squared upper end of a rod E, preferably metallic, and with a sufficient amount of flexibility and spring. The lower end of this rod is squared and fits into a passage F' in the plug or core F, provided 50 with peripheral longitudinal grooves F', said plug fitting within the tube H. This plug F and its relation with the tube H correspond

exactly with the plug D and its relation to the tube C. A flexible tube K, made preferably of mineralized rubber, extends from the tube 55 C to the tube H, being secured to said tubes by means of the annular ribs C' and H' or in any suitable manner. The lower end H'' of the tube H is internally screw-threaded and provided with the integral hand ring or nut 60 *h*. Into this portion H'' screws the tube J, externally screw-threaded at its upper portion and provided with a hand-nut L, between which and the lower end of the tube H H'' suitable packing N is placed. This tube J is 65 formed with an integral flange P, whereby it is held in the tube R, and the long extension J'. This tube R is provided with the internal flange R' and screwed upon the tube S, which is screwed into the mouth of the can A 70 and fits around the extension J' of the tube J. Suitable packing T is provided within the tube or between the tube S and the flange P.

The nut L is properly a hand-nut, as above designated, rather than a check-nut, as its object is to be held by one hand while the nozzle proper is screwed up and seated against it, thus enabling the nozzle to be rotated by grasping it at any point. When the nozzle proper is to be removed, the hand-nut L is held 75 stationary by one hand. If desired, a little solder may be applied to unite the hand-nut with the pipe J.

It will be noticed that the parts lastnamed constitute something more than an ordinary 85 union, the tube J being provided with the long extension J', which reaches to the mouth of the can itself, thus imparting great stiffness and strength at that point.

When the can is in use and sufficient force 90 is suddenly applied to the nozzle to bend or break one constructed in the ordinary manner, my improved nozzle yields and bends between the tubes C and H by means of the flexible connecting-tube K, but is prevented 95 from collapse and immediately restored to its original straight position when the force is removed by the pliable springing rod E. Thus the nozzle yields, but does not break or become permanently bent.

Having thus fully described my invention, what I claim, and desire to secure by Letters Patent, is—

1. A nozzle for oil-cans, comprising two sep-

arate, rigid tubular portions, a flexible, tubular connection thereof, and a flexible spring-rod extending through said flexible tubular connection and secured at its opposite ends within said rigid tubular portions, substantially as set forth.

2. In a nozzle for oil-cans, two separate rigid, tubular portions, cores, or plugs within said portions and provided with passages for the oil, a suitably flexible spring-rod connecting said plugs or cores, and a flexible tube surrounding said rod and connecting said tubular rigid portions, substantially as described.

3. In a nozzle for oil-cans, the combination of the tube C sustaining the tip B, the core or plug D fixed in said tube and provided with the longitudinal peripheral grooves D', the tube H connected by a union or coupling with the oil-can, the core or plug F rigid within said tube H and provided with the longitudinal peripheral grooves F', the spring-rod E hav-

ing its opposite ends fast in said plugs or cores D F, and a flexible tube K surrounding said rod and connecting the tubes C H, substantially as set forth.

4. In a nozzle for oil-cans, the combination of the internally-screw-threaded tube H, the internally-screw-threaded tube R provided with the internal flange R', the externally-screw-threaded tube S screwing into said tube R, and externally-screw-threaded tube J screwing into the tube H, provided with the flange P and with the stiffening extension J' extending down into the said tube S, whereby the nozzle is rendered rotative and capable of being taken apart and its parts assembled, substantially as set forth.

DAVID TRUE.
